UNITED STATES PATENT OFFICE.

SAMUEL H. WELLS, OF OXFORD, MISSISSIPPI.

PORTABLE FENCE.

1,131,302.

Specification of Letters Patent.

Patented Mar. 9, 1915.

Application filed December 16, 1913. Serial No. 807,111.

To all whom it may concern:

Be it known that I, SAMUEL H. WELLS, a citizen of the United States, residing at Oxford, in the county of Lafayette and State of Mississippi, have invented new and useful Improvements in Portable Fences, of which the following is a specification.

The invention has relation to means for inclosing a parcel of ground either to corral stock or to prevent trespass, the purpose being to provide inclosing means of a portable character which may be quickly and conveniently set up or taken down and which may be readily handled for transportation or storing.

The invention provides inclosing means comprising panels of predetermined length and height and means for securing such panels along the prescribed line of the boundary or piece of ground to be inclosed, the securing means being of such a nature as to insure a reliable structure and to be capable of being quickly placed in position or removed according to requirements.

The invention consists of the novel features, details of construction and combination of parts, which hereinafter will be more particularly set forth, illustrated in the accompanying drawings, and pointed out in the appended claim.

Referring to the drawings, forming a part of the specification, Figure 1 is a perspective view of the invention, showing the corner portion of a parcel of ground inclosed by a fence embodying the invention. Fig. 2 is a detail view of the adjacent ends of two fence panels located at one of the corners of an inclosure. Fig. 3 is a cross section of a fence panel, showing more clearly the bracing means.

Corresponding and like parts are referred to in the following description, and indicated in all the views of the drawings, by the same reference characters.

In accordance with this invention the means for inclosing a piece of ground consists of a plurality of panels which may be of similar or like construction, the single panels being practically of a uniform size so as to be placed in a pile for convenience of storing. The panels are preferably of a size and construction to be easily handled by one person. Each of the panels comprises uprights 1 and longitudinal rails 2, the latter being provided in pairs and arranged at or near the top and the bottom of the panel

with the uprights 1 between the rails of each pair, the several parts being secured at their points of crossing by nails or like fastenings driven therethrough. The space between the upper and lower rails may be occupied by filling wires 3, which may be of any variety and which are stapled or otherwise secured to the uprights 1. It is preferred to extend the uprights above the upper rails a short distance and to have the upper filling wire secured thereto. The ends of the longitudinal rails which are provided in pairs project a short distance beyond the extreme uprights to overlap and interlock thereby preventing lateral displacement of the panels. Pegs 4 are driven between the ends of the lower rails against the inner edges of the end uprights and penetrate the ground to a depth to insure a firm holding of the parts in place. The panels bordering upon the corner of an inclosure have the projecting ends of the inner rails cut away to admit of the corners overlapping, thereby providing a substantial joint, the contiguous ends being made secure by means of a binder 6, which consists of a wire wrapped about the adjacent corner uprights.

When setting up the fence the panels are arranged along the prescribed course in such a manner as to cause the projecting ends of the rails to interlock, the pegs 4 being driven into the ground between the lower longitudinal rails, thereby preventing both lateral and longitudinal movement of the panels. Brace wires 7 are passed about the upper rails and extend upon opposite sides of the panels with their lower ends secured to the ground by means of pins 8 driven therein. It is to be understood that the brace wires may be located any distance apart in order to provide a substantial structure. The ends of the brace wires are formed into eyes and the pins 8 after being passed through such eyes are driven into the ground, the pins being headed to engage the eyes and insure a tightening of the brace wires.

From the foregoing, taken in connection with the accompanying drawings, it will be understood that the invention provides a fence or inclosing means which may be utilized for corralling stock, or for other purposes, to prevent trespass upon a tract of land, said fence being of a nature to be quickly set up or taken apart, as the pins 8 and pegs 4 may be quickly withdrawn so that the panels may be moved from one place

to another or stored in compact form for future use.

From the foregoing description, taken in connection with the accompanying drawings, 5 the advantages of the construction and of the method of operation will be readily apparent to those skilled in the art to which the invention appertains, and while I have described the principle of operation of the 10 invention, together with the device which I now consider to be the best embodiment thereof, I desire to have it understood that the device shown is merely illustrative, and that such changes may be made when de- 15 sired as are within the scope of the claim appended hereto.

Having thus described the invention what is claimed as new, is:—

20 A portable fence comprising like panels of uniform size, each of such panels comprising upper and lower pairs of longitudinal rails, uprights secured between the pairs of longitudinal rails, the latter having their end portions projecting beyond the end up-

rights to admit of the projecting ends of the 25 longitudinal rails interlocking by interfitting, the uprights projecting above the upper longitudinal rails, longitudinal wires secured to the uprights of each panel between and above the longitudinal rails, pegs adapted to be driven into the ground between the lower pairs of longitudinal rails against the end uprights of adjacent panels, brace wires 30 engaging the upper rails and adapted to be secured at their lower ends to the ground 35 upon opposite sides of the panels, the corner panels having the outer longitudinal rails projecting to overlap the end uprights of contiguous panels, and a binder for securing the corner panels by engaging the ad- 40 jacent uprights.

In testimony whereof I affix my signature in presence of two witnesses.

SAMUEL H. ^{his} ~~mark~~ WELLS.
